UNITED STATES PATENT OFFICE.

JANE R. MILLER AND ABRAHAM H. MILLER, OF LOS ANGELES, CALIFORNIA.

DESIGN FOR A BALLOON ADVERTISING SIGN.

Application filed January 21, 1929. Serial No. 29,719. Term of patent 7 years.

To all whom it may concern:

Be it known that JANE R. MILLER and ABRAHAM H. MILLER, citizens of the United States, residing at Los Angeles, county of Los Angeles, State of California, have invented a new, original, and ornamental Design for Balloon Advertising Signs, of which the following is a specification, reference being had to the accompanying drawing, forming a part thereof.

The figure is the front elevation of a balloon advertising sign showing our new design.

We claim:

The ornamental design for a balloon advertising sign as shown.

JANE R. MILLER.
ABRAHAM H. MILLER.
